HUMIDIFIER AND CATHETER UNIT

Samuel Y. Gibbon, Jenkintown, Pa., assignor to Air Shields, Inc., Bucks County, Pa., a corporation of Delaware

Application June 1, 1954, Serial No. 433,371

6 Claims. (Cl. 128—1)

This invention relates to humidifying equipment and is particularly concerned with apparatus suitable for therapeutic use with an enclosed occupant's chamber which may also be used for an additional therapeutic function besides supplying humidification.

The apparatus is especially useful in connection with treatment of infants and children where they require a highly humidified atmosphere, such as when suffering from croup or other ailments of the nose, throat or lungs. In such ailments besides the need for a high humidity to soothe and moisten the membranes and loosen the excess mucus, it is also desirable to remove this mucus from the trachea to allow easier breathing. For this purpose a catheter is generally used.

It is the primary object of the present invention to combine the humidifier and the catheter required for such ailments into a single, compact unit. This unit uses the same source of power and same suction producing apparatus to operate both the humidifier and the catheter.

It is also a specific object of the invention to provide an atomizer unit, the suction side of which may be selectively connected either to a liquid source for operating the humidifier or to a low pressure chamber associated with the catheter system.

How these and other objects and advantages incidental to the invention are attained will be clear from the following description of the drawings, in which—

Figure 1 is a view of an enclosed bassinet unit having the apparatus of the present invention attached thereto.

Figure 2 is a plan view of the apparatus of the present invention to an enlarged scale with the vertical delivery pipe shown in section.

Figure 3 is a front elevational view of the apparatus having certain parts broken away for convenience.

Figure 4 is a sectional view through the body of the apparatus showing the humidifier liquid container and the atomizer unit, the view being taken along the line 4—4, Figure 2.

Figure 5 is a sectional view through the body of the apparatus showing the mounting and connecting construction for the low pressure catheter chamber, the view being taken along the line 5—5, Figure 2.

Referring to Figure 1 there is shown an enclosed bassinet unit 10 having a lid 11 which is hinged at the middle to allow access to either end of the chamber. In the arrangement shown, the bassinet 10 is part of an infant's rocking bed which may be used to assist breathing functions in ailments where breathing is difficult. The bassinet or chamber 10 is supported in a cradle structure having vertical side members 12. These in turn are attached to frame structure having members 13 and 14 by means of pivot bearings supported in housing 15. By this construction a transverse rocking axis is provided near the head end of the chamber. Rocking motion is induced by means of arm 16 and link 17 which are actuated by suitable drive mechanism not shown. The bassinet unit forms no part of the present invention per se

2

but serves to illustrate a typical application for the humidifier-catheter system which is shown connected to the head end of the chamber.

The unit shown includes a body 18 which is supported on the rocking bed. From the body 18, a delivery duct 19 for conveying humidified atmosphere, extends upwardly and is connected to feed through an opening into the bassinet 10. A catheter tube 20 also extends from the upper side of the body member 18 and may pass through an opening in the wall of bassinet 10 to the inside where it is available for use in withdrawing mucus from the patient's nose or throat.

The detail construction of the humidifier-catheter unit will be more clearly observed in Figures 2 to 5 inclusive. The delivery duct 19 is fastened to the base or body 18 by two screws 21. As is best seen in Figure 4 an atomizer 22 is supported on the body 18 by a fitting 23. Two tubes 24 and 25 extend from fitting 23 to the atomizer 22. Attached to fitting 23 and connecting with tube 24 is a flexible hose 26 which is used to connect to a gas supply under pressure such as a compressed air line or an oxygen bottle. Tube 24 connects to the central outlet 27 of the atomizer nozzle and is in line with the aperture 28 in the end of outer shell 29 of the atomizer. Between the outer shell 29 and the inner body 30 there is formed a cavity 31. Tube 25 is connected to cavity 31 by the hole 32 through body 30. The lower end of tube 25 connects to annular passage 33 which in turn is connected to flexible hose 34, one end of which is firmly attached to the body 18 in a suitable fashion as indicated by fitting 34a.

The delivery of gas under high pressure to the central opening 27 of the nozzle causes a low pressure in the cavity 31, thus producing a suction action in the tube 34 which is connected to the cavity 31. As will be seen from Figures 2, 3 and 5, the other end of flexible hose 34 may be attached to the body 18 at the outlet fitting 35. It will be seen that the inside of fitting 35 incorporates a hole having a slight taper to fit the tapered end 36 of fitting 37 attached to the end of hose 34. This tapered fitting allows rapid attachment or removal of fitting 37 and at the same time produces a pressure tight connection.

Attached to body 18 is a jar or chamber 38 shown in Figures 2 and 3 but omitted from Figure 5 to better show other parts. Chamber 38 is the same as chamber 38a mounted at the opposite side of body 18 and shown in Figure 4. Thus a threaded support 39 is secured to the body 18 to permit the chamber 38 to be quickly attached or detached. A ring seal 40 engages the upper lip of the chamber 38 to provide a pressure tight chamber. Connected to this chamber by means of channel 41 is the flexible tube 34. Also attached to the chamber is catheter tube 20 which engages pressure tight fitting 42 which connects through body 18 to the upper end of chamber 38. Fitting 43 is attached to the end of catheter tube 20 to provide the connection to fitting 42.

Thus the suction action produced in tube 34 causes a lowered pressure in chamber 38 resulting in a suction in catheter tube 20. When the catheter is in use, the suction causes the mucus to be drawn into tube 20 and carried to the chamber 38 where it is deposited. As has been noted chamber 38 is readily removable for cleaning and sterilizing.

As has been mentioned, a similar jar or chamber 38a is also supported on body 18. Chamber 38a serves as a reservoir for the fluid which may be supplied to the atomizer when it is being used for humidifying purposes. Chamber 38a is clearly shown in Figures 2, 3 and 4. It will be seen that a threaded supporting fitting 39a similar to fitting 39 is mounted in the body 18 and a seal 40a is also provided. As will be evident fitting 35a connects to a flexible tube 44 which extends to the bottom of cham-

ber 38a and is equipped with a fine mesh screen 45 to prevent particles of dirt from getting into the system and clogging the atomizer.

The fitting 35a is equipped with a tapered bore to engage the fitting 37 on the end of tube 34. Thus tube 34 may be removed from the catheter system and connected with the humidifier system by attaching to fitting 35a. The suction action produced in tube 34 draws up liquid from the chamber 38a and delivers it to the atomizer nozzle through outlet 27. Here it is broken up into fine particles which are carried by the atomizer flow upwardly through the delivery duct 19 to the occupant's chamber 10. The nozzle of the atomizer breaks the liquid particles into a fine mist. Any oversize particles impinge against the walls of the duct as they move through the duct and particularly at the elbow. Such particles collect on the inner wall and run down to the bottom of the duct where they collect and run back into chamber 38a through the drain channel 46. It will be obvious that if desired, medications such as aerosols may be delivered as a vapor by the atomizer system.

Brackets 47 are attached to body 18 to provide for the support of the unit on a wall or other supporting structure.

From the foregoing it will be evident that I have provided an improved piece of equipment for use in connection with ailments of the nose, throat and lungs. This compact device incorporates in a single apparatus two of the most effective means for relieving distress in such ailments. The atomizer unit thus provides the common means for operating both the humidifying system and the catheter system. The flexible tube with the quick connectible fitting allows the operator to easily change from one system to the other with no loss of time.

I claim:

1. Apparatus suitable for supplying humidified oxygen to an enclosed chamber including a base having a delivery duct extending upwardly therefrom, an atomizer mounted on said base and located in the lower end of said duct, a channel leading from said atomizer, a connecting fitting for the delivery of gas through said channel under pressure, a second channel from said atomizer to a second fitting in said base adjacent the bottom of said duct, a flexible external hose attached to said fitting, the opposite end of said hose being equipped with a quick-detachable fitting, a fluid container attached to said base, a tube leading from the bottom of said container to a terminal fitting on said base, said terminal fitting being formed to receive said quick-detachable fitting on said hose.

2. A construction in accordance with claim 1 in which a second container is mounted on said base, a tube extending from the base above said second container, said tube having a flexible portion to be used as a catheter, another channel in the base leading from the top of the second container to a terminal fitting at the outside of the base, said terminal fitting also being formed to receive the quick-detachable fitting on said hose thereby

permitting the atomizer unit to supply suction to said second container for operating the catheter.

3. A combined humidifier and catheter unit having two containers, one of which is used to hold humidifying liquid and the other serves as the receptacle for the catheter, an atomizer, a duct extending upwardly from said atomizer, a connecting channel to said atomizer for supplying gas under pressure, a second channel to said atomizer in which a negative pressure is developed when the first channel is supplied with gas under pressure, a flexible hose connected to said second channel, connecting means on the other end of said hose for connecting either to said liquid container or to said catheter container and a tube connected to the upper portion of said catheter chamber.

4. A combination humidifier and catheter device having an atomizer member, a duct in which said atomizer is supported, a connection to said atomizer for supplying gas under pressure, a container for holding humidifying liquid, a flexible connection between said container and said atomizer, said flexible connection having a disconnectible fitting at the end connected to said container, a second container having a catheter tube attached to the upper portion thereof, a terminal having a channel leading to said catheter container, said terminal being connectible to the disconnectible fitting of said flexible connection when it is desired to use the device as a catheter system.

5. A construction according to claim 4 in which the flexible connection is equipped with a friction fit terminal and two cooperating fittings are provided, one for connection to the liquid container and one for the catheter container.

6. A humidifier and catheter unit constructed for attachment to an infant's therapeutic chamber including a supporting block, an atomizer unit supported on said block, a duct attached to said block leading upwardly therefrom, a pair of containers supported on the under side of said block, one of said containers serving as a fluid reservoir and having a tube leading from the bottom of the container to a fitting on the block, the other container having a channel leading from the top of the container to a second fitting in the block, a catheter tube leading from the block above the second container, a flexible hose connected at one end to a fitting adjacent said atomizer, the other end of said hose being equipped with a readily detachable fitting which may be attached to the fitting connected to the fluid container or the fitting connected to the catheter container.
